(57) **CLAIM**

The ornamental design for a fluorescent lamp, as shown and described.

DESCRIPTION

FIG. 1 is an isometric view showing the front, top and left side of my ornamental design for a light fixture, with phantom lines indicating such utilitarian features as stand offs and an electric cord which form no part of the claimed design.

FIG. 2 is a left side elevational view of the fixture of FIG. 1;

FIG. 3 is a right side elevational view of the fixture of FIG. 1;

FIG. 4 is a top plan view of the fixture of FIG. 1;

FIG. 5 is a front elevational view of the fixture of FIG. 1;

FIG. 6 is a bottom plan view of the fixture of FIG. 1; and,

FIG. 7 is a rear elevational view of the fixture of FIG. 1 with phantom lines indicating utilitarian features which form no part of the claimed design.
